DESIGN FOR A TOY FIGURE

Lawrence C. Boll, Minneapolis, Minn.

Application February 22, 1945, Serial No. 118,080

Term of patent 7 years

(Cl. D34—15)

To all whom it may concern:

Be it known that I, Lawrence C. Boll, a citizen of United States and residing in the city of Minneapolis, county of Hennepin, State of Minnesota, have invented a new, original, and ornamental Design for a Toy Figure, of which the following is a specification, reference being made to the accompanying drawing, forming a part thereof, wherein:

Fig. 1 is a side elevational view of a toy figure showing my design;

Fig. 2 is a front elevational view of the same;
Fig. 3 is a rear elevational view of the same;
and,

Fig. 4 is a top plan view.

I claim:

The ornamental design for a toy figure, as shown.

LAWRENCE C. BOLL.
